UNITED STATES PATENT OFFICE.

FREDERICK A. ENGLISH, OF CHICAGO, ILLINOIS, ASSIGNOR TO BIRTMAN ELECTRIC COMPANY, OF CHICAGO, ILLINOIS, A CORPORATION OF ILLINOIS.

VACUUM CLEANER.

Application filed October 7, 1922. Serial No. 592,988.

To all whom it may concern:

Be it known that I, FREDERICK A. ENGLISH, a citizen of the United States, residing at Chicago, in the county of Cook and State of Illinois, have invented a new and useful Improvement in Vacuum Cleaners, of which the following is a specification.

My invention relates to certain new and useful improvements in vacuum cleaner and 10 is fully described and explained in the specification and shown in the accompanying drawings, in which—

Figure 1 is a view in side elevation, Fig. 2 is a fragmentary bottom plan view, and 15 Fig. 3 is a fragmentary vertical sectional view.

As shown in the drawings, 10 indicates in general the housing of a vacuum cleaner of common form supported by the ordinary 20 two forward wheels 11 and the single back castor wheel 12. 13 indicates the elongated suction nozzle or mouth of the cleaner, which is also of the ordinary form. The slot-like opening in this nozzle or mouth is shown 25 in bottom plan view in Fig. 2, as indicated by 13^a. The parts heretofore described constitute parts of a vacuum cleaner of common form.

20 indicates a tube, substantially the same 30 length as the slot 13^a, provided throughout its length with bristles 20^a, thus forming a long brush which may hereafter be referred to as the brush 20^a. 21 indicates a similar tube somewhat shorter than the tube 20, arranged parallel thereto and spaced therefrom, which is likewise provided throughout its length with bristles 21^a, thus forming a brush which may hereafter be referred to as the brush 21^a. The two tubes, 20 and 21, 35 are spaced from each other by a pair of straps 30. The tube 21 is pivotally mounted at its ends between two supports 22 attached to the rear side of the suction nozzle 13. Said straps 30 offset the brush 20^a a 40 greater distance from its axis of swinging movement than a direct line to the surface to be cleaned so that said brush 20^a, as shown in dotted lines in Fig. 1, cannot accidentally move or be moved to its inoperative position until the forward end of the vacuum cleaner has been raised.

The two tubes with the two straps 30 form a sufficiently rigid frame pivotally attached to the nozzle 13 at the ends of the 45 tube 21. This frame may be pivoted on the

ends of the tube 21 to swing the brushes into operative position or into inoperative position. In Fig. 1, the brushes are shown in inoperative position in the solid lines and in operative position in the broken lines. 60 It will be noted that when the brushes are in operative position, the brush 20^a will be in advance of the nozzle 13 and parallel thereto, with the lower ends of the bristles projecting slightly below the lower edge of the 65 nozzle, so they will engage the surface being cleaned. When in this position, the brush 21^a will be similarly arranged behind the suction nozzle. When the brushes are swung into inoperative position, as indicated by the 70 solid lines in Fig. 1, the brushes will be folded up under the slanting part 50 of the nozzle, with the bristles pointing upwardly, where the brushes will be out of the way and will not engage with the surface being 75 cleaned.

In order to hold the brushes yieldingly in operative position (see Fig. 3) the straps 30 are made of spring metal, and the ends near the tube 20 are bent upwardly and backwardly slightly (as viewed in Fig. 3, showing the brushes in operative position) as indicated by 30^a. When the brushes are swung into operative position, these parts 30^a of the straps 30 spring over the lower forward 80 edge of the nozzle 13 and then snap back slightly to clamp or clasp (the forward edge of the nozzle 13 sloping backward) thus yieldingly holding the brushes in operative position. Each of the straps 30 is also provided with an upwardly rounded part 30^b 85 adapted to enter the slot 13^a when the brushes are swung into operative position.

A spiral spring 60 is provided on one end of the tube 21 for the purpose of yieldingly 90 holding the brushes in inoperative position. The snapping or locking effect of the parts 30^a of the straps 30 is, however, sufficiently strong to overcome the resistance of the spiral spring 60, so that the brushes will 100 be yieldingly snapped or locked in operative position.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim 110

all novelty inherent in my invention as broadly as possible in view of the prior art.

What I claim as new and desire to secure by Letters Patent, is:

6. 1. In combination with a vacuum cleaner having a suction nozzle, a plurality of spaced apart brushes disposed in the front and rear of the said nozzle when in operative relation thereto, a brush-carrying frame 10 carried by the nozzle exteriorly thereof in either operative or inoperative relation therewith, means carried by said frame and engaging the nozzle to prevent accidental swinging movement of said frame from operative position, and means carried by the frame to prevent its accidental swinging from inoperative position.
2. In combination with a suction nozzle, a brush exteriorly of the nozzle to engage the 20 surface to be cleaned, means exteriorly of the nozzle connecting the brush to the nozzle for movement while connected to the nozzle to an operative position and to an inoperative position, said means being engageable with the inner and outer walls of the nozzle to operatively position the brush, and means to maintain the brush against accidental displacement from inoperative position.
- 30 3. In combination with a suction nozzle of a vacuum cleaner or the like, a brush, brush mounting means pivotally connected to the exterior of the nozzle and adapted to engage the surface to be cleaned, means urging said brush to an inoperative position, and means carried by said brush-mounting means disposed across the nozzle offsetting the sweeping surface of the brush from its axis of swinging movement a greater distance than 40 the direct vertical distance between said axis and the surface to be cleaned.
4. In combination with a suction nozzle, a brush located exteriorly of the nozzle and pivotally connected thereto and adapted to 45 engage the surface to be cleaned, means in operative position interiorly and exteriorly engaging the wall of the nozzle and offsetting the sweeping surface of said brush from

its axis of swinging movement a greater distance than the direct vertical distance between said axis and said surface, and means to maintain the brush against accidental displacement from inoperative position.

5. In combination with a nozzle, a brush pivoted thereto and operative at the rear thereof, a brush operative at the front of the nozzle, means joining said brushes and clamping them to the nozzle in operative position, and a spring coacting with the first brush and the nozzle and urging inversion of both brushes and movement of the second brush to a position rearwardly of the nozzle.

6. In combination with a suction nozzle of a vacuum cleaner or the like, brushes adapted for engagement with the surface to be cleaned disposed on opposite sides of the nozzle and connected thereto for unitary movement to an operative position and to an inoperative position, said brushes being invertible through said movement from one position to the other position, straps spanning said brushes, said straps being constructed for clamp engagement with the inner and outer surfaces of the wall of the nozzle and for application thereto in the direction of suction, and means to maintain said brushes in the inoperative position.

7. In combination with a vacuum cleaner having an elongated suction nozzle, a frame carrying a pair of brushes exteriorly of the nozzle, means pivotally connecting said frame to the cleaner so that the brushes may be moved unitarily with the frame and simultaneously in the same direction from operative position with one in front of and one behind the nozzle, and both in engagement with the surface being cleaned, into inoperative position with both behind the nozzle and out of engagement with the surface being cleaned, and means to maintain the frame and brushes in inoperative position.

Witness my hand this 5th day of October, 1922.

FREDERICK A. ENGLISH.
